Des. 188,387
Patented July 12, 1960

188,387

MOVABLE BEAD ROSARY

Albert J. Hoban, 200 Essex Road, North Kingstown, R.I.

Filed Dec. 14, 1959, Ser. No. 58,657

Term of patent 14 years

(Cl. D45—16)

FIG. 1

FIG. 2

FIG. 3

FIG. 4

FIG. 5

FIG. 6

Figure 1 is a perspective view of a movable bead rosary showing my new design.

Figure 2 is a plan view of the rosary shown in Figure 1.

Figure 3 is a side elevational view thereof.

Figure 4 is a left hand end view thereof.

Figure 5 is a right hand end view thereof, and

Figure 6 is a bottom view of Figure 2.

I claim:

The ornamental design for a movable bead rosary, as shown.
